UNITED STATES PATENT OFFICE.

WILLIAM DAVID CARNAL, OF AKRON, OHIO, ASSIGNOR TO RAY PUNCTURE PROOF TIRE COMPANY, OF CHICAGO, ILLINOIS, A CORPORATION OF ILLINOIS.

DESIGN FOR A TIRE.

Application filed May 10, 1921. Serial No. 468,428. Term of patent 14 years.

To all whom it may concern:

Be it known that I, WILLIAM DAVID CARNAL, a citizen of the United States, residing at Akron, in the county of Summit and State of Ohio, have invented a new, original, and ornamental Design for Tires, of which the following is a specification, reference being had to the accompanying drawings, forming a part thereof.

Figure 1 is a plan view of a portion of a tire, showing my new design, and,

Figure 2 is a transverse sectional view of same taken on the line 2—2 of Figure 1.

I claim:

The ornamental design for a tire as shown.

WILLIAM DAVID CARNAL.
